UNITED STATES PATENT OFFICE

171,096

ORGAN CONSOLE

William Millington, Grand Rapids, Mich., and
Wilbur M. Day, Kenwood, Ohio, assignors to
The Baldwin Company, Cincinnati, Ohio, a cor-
poration of Ohio

Application February 5, 1953, Serial No. 23,453

Term of patent 14 years

(Cl. D56—2)

To all whom it may concern:

Be it known that we, William Millington and Wilbur M. Day, have invented a new, original, and ornamental Design for an Organ Console, of which the following is a specification, reference being had to the accompanying drawing, forming a part hereof.

The figure is a perspective view of an organ console showing our new design.

We claim:

The ornamental design for an organ console, substantially as shown.

WILLIAM MILLINGTON.
WILBUR M. DAY.
